DEVICE FOR TRANSPORTING GRIPPER SHUTTLES IN A LOOM

Erwin Pfarrwaller, Winterthur, Switzerland, assignor to Sulzer Frères, Société Anonyme, a corporation of Switzerland

Application March 31, 1954, Serial No. 420,103

Claims priority, application Switzerland April 11, 1953

12 Claims. (Cl. 139—125)

The present invention relates to a device for transporting gripper shuttles in a loom from a conveyor returning idle shuttles into the position from which the shuttles are picked after having a weft thread connected therewith. The new device comprises a shuttle transfer element or shuttle carrier which is swingable on a shaft. The bearings of the latter are movable at a right angle to the shuttle picking path.

The novel features which are considered characteristic of the invention are set forth with particularity in the appended claims. The invention itself however and additional objects and advantages thereof will best be understood from the following description of an embodiment thereof when read in connection with the accompanying drawing in which

Fig. 1 is a diagrammatic illustration of a loom for weaving as seen from the cloth beam side;

Fig. 2 is a cross-sectional view of a part of the picking mechanism according to the invention;

Fig. 3 illustrates a portion of Fig. 2 showing an opener for a weft thread clamp mounted on a shuttle;

Fig. 4 is a part-sectional top view of the mechanism shown in Figs. 2 and 3;

Fig. 5 is a top view of a shuttle carrier or lifter according to the invention;

Fig. 6 is a longitudinal sectional view of a portion of the picking and shuttle return mechanism according to the invention;

Fig. 7 illustrates the shuttle lifter according to the invention in a plurality of operating positions;

Figs. 8 to 10 are kinematic diagrammatic illustrations of the mechanism according to the invention in three different operation positions.

The same numerals designate the same parts in all figures.

Referring more particularly to Fig. 1 of the drawing, the drive of the loom includes a motor 11 which is mounted on a right side shield 12 and which drives a belt pulley 14 by means of a belt 13. A disc clutch mounted in the pulley 14 and not shown drives the main shaft 15 of the loom. The shaft 15 primarily drives the parts of the loom which must be moved permanently or intermittently during normal operation of the loom. The shaft 15 actuates the warp beam 16 and the warp 17 which moves through the heddles supported by one or a plurality of frames 18, the latter being actuated by the shaft 15 for opening, closing, and changing of the shed. The shaft 15 also actuates the warp actuating beam 19 and the cloth beam 20 for winding the cloth 21.

A picking mechanism 22 and a shuttle receiving mechanism 23 are also driven by the shaft 15 by means of intermediate drives. A weft thread 25 is transferred to a shuttle 24 in the picking mechanism 22. The weft thread is pulled from a spool 27 supported by a carrier 26 outside of the shuttle 24 and is picked by the shuttle 24 through the shed towards the receiving mechanism 23,

2

whereupon the weft thread 25 is beaten up by means of a lay actuated by the shaft 15.

The shuttle 24, after the weft thread 25 has been disengaged therefrom, is moved onto a return mechanism 28 by suitable means in the receiving mechanism 23. The return mechanism, driven by the main shaft 15, returns the idle shuttle 24 below the shed from the receiving mechanism to the picking mechanism.

A drive 31 for a fabric control beam 19 is mounted on a left side shield 29 which is connected with the right side shield 12 by means of a box girder 30 to form a rigid frame for the weaving machine. The angular position of the beam 19 relatively to the zero position of the main shaft 15 can forwardly and backwardly be changed by means of a hand wheel 32 by means of a suitable control mechanism.

Control levers 33 and control shaft 34 afford actuation of the above mentioned clutch by means of a linkage 35 and of a brake disk by means of a linkage 36 for starting 20 and stopping the loom from both sides of the loom. The brake, which is in a housing 37 and mounted on the main shaft 15, is applied at improper operating conditions after disengagement of the disk clutch in the belt pulley 14 for immediately stopping the main shaft 15 and all parts driven thereby. The brake in the housing 37 is disengaged in known manner by means of a control lever 33 without engaging the clutch in the disc 14. Thereupon the disconnected main shaft 15 can be turned by means of a handwheel 38 so that the loom parts driven 30 thereby assume a desired position for restarting the loom.

As seen in Fig. 2, a shaft 40 supporting a cam element 41 is revolvably supported in the casing 22 of a shuttle picking mechanism. The shaft 40 is revolved through a bevel gear wheel 42 by the main shaft 15 of the loom by 35 conventional means, not shown. The cam element 41 is in the shape of a drum having two cam grooves 43 and 44, in which run cam follower rollers 45 and 46, respectively, which are mounted on two-arm levers 47 and 48, respectively. The levers 47 and 48 swing on shafts 49 and 50, respectively, which are supported by the casing 22. A link 51 is pivoted to the upper end of the lever 48, the link being pivoted by a pin 60 to a shuttle carrier or lifter 52. The latter is provided with a shuttle receiving channel 53 and rests on a plate 54, if it is in the position shown in Fig. 2. The lifter 52 can be swung 45 on a pivot 55 for transporting a shuttle 59 to the horizontal picking position. The lever 47 is pivoted to a link 56 which is connected by means of a bolt 60 (Fig. 3) with an opener 57 for a clamp 58 in the shuttle 59. The clamp opener 57 is supported coaxially of the shuttle lifter 52 and revolves on an axis 55.

The axis or shaft 55 is supported by a slide 62 which is movable in two guides 63 (Fig. 4). The latter are closed on top by cover plates 61 connected with the casing 55, one of the plates 61 serving as an abutment for the shuttle lifter 52 when the latter is in the position from which the shuttle is picked. The slide carrying the shaft 55 is formed as a bracket guided by the guides 63 and has a guide rod 65 connected thereto. The rod 65 has a 60 collar 66 against which abuts one end of a compression spring 67. The rod is surrounded by an annular member 68 which is loose on the rod 65 and abuts against the other end of the spring 67. The member 68 abuts against a projection 69 of the casing 22 and guides the rod 65 in a bore 70.

The spring 67 abutting against the member 68 and thereby against the casing 22, urges the collar 66 and the rod 65 with the slide member 62 to the right until it abuts 70 against the stationary abutments 64. A retainer ring 71 inserted in an annular groove of the rod 65 holds the member 68 and the spring 67 on the rod, when the slide 62 is

dismantled. The upper end of the lever 47 is provided with a fork 72 receiving the rod 65.

The shuttle lifter is shown in Figs. 2 and 6 in its lowest shuttle receiving position, the shuttle 59 being pushed into the shuttle receiving channel 53 of the lifter 52 by means of a pusher 74 which is inserted in a roller chain laid around a chain wheel 73 and which forms part of a shuttle return mechanism 28.

If, due to an operating irregularity, two shuttles 59 are pushed along by a pusher 74, the first shuttle would 10 push away a plug 83 which is held in position by a weak plate spring 82 and the second shuttle would be pushed to the correct position in the channel 53. The plug 83 normally serves merely as an abutment.

In Figs. 3, 4 and 5 the shuttle lifter 52 is shown in the horizontal position from which a shuttle 59, which is in the picking path 75, may be picked. After a weft thread 25 has been connected with the shuttle in the conventional manner, the opener 57 is pulled out of the clamp 58. The cam groove 43 causes counterclockwise rotation of the lever 47 rotating the opener 57 while the lifter 52 remains in the horizontal position. The shuttle 59 may now be accelerated and picked through the shed by means of a picker 76 having a picking element 77 and a picking pin 78.

The weft thread 25 unwound from the spool 27 which is held to the shuttle 59 by means of the clamp 58 is covered by the cover 79 which closes part of the top of the channel 53 (Fig. 5). The cover 79 has an arcuate edge 81. If the shuttle lifter 52 would be swung back on the axis 55 in position O (Fig. 7), from picking position to shuttle receiving position, the cover 79 would engage and take the weft thread along until the thread slides off the edge 81.

Sensitive yarns may be greased or blackened when contacting the edge 81. For this reason, the return path of the shuttle lifter 52 is different from the path toward the picking position. After the shuttle 59 has been picked, the parts of the mechanism according to the invention are in the position shown in Fig. 8. In order to prevent contact of the weft thread 25 with the shuttle lifter 52 and the cover 79, the cam groove 43 is so formed that the lever 47 is revolved counterclockwise until the fork 72 abuts against the collar 66 and compresses the spring 67. The slide 62 is thereby pulled to the left (Fig. 9). Not until then is the lever 48 actuated for revolving the shuttle lifter 52 on the axis 55.

Fig. 7 illustrates different positions of the shuttle lifter 52. The point corresponding to the thread 25, i. e. the longitudinal axis of the shuttle 59, moves from point O via point 1 to point 2, the lever 48 as well as the lever 47 moving according to the configuration of the cam grooves 44 and 45 until the parts reach the position shown in Fig. 9.

The movement of the lever 47 is reversed to the clockwise direction after the longitudinal axis of the shuttle has reached the point 2, so that the receiving channel 53 is turned downwards and the longitudinal axis of the shuttle passes successively through the points 3, 4, 5, and 6 (Fig. 7). Due to the clockwise rotation of the lifter 47, the spring 67 is released and the slide 62 is moved to its right extreme position (Fig. 10). The shuttle clamp opener 57 has arrived in its low starting position in which the opener clears the channel 53 for receiving a shuttle. In the position of the lever 47 shown in Fig. 9, the opener 57 has moved to the left beyond the starting position.

The use of the lever 47 for moving the slide 62 has the advantage that only a few additional parts are needed and additional grooves, requiring a longer member 41, are avoided.

The support of the pin 55 in the slide 62, the guidance of the rod 65 in the member 68, and the use of relatively long links 51 and 56, which are almost at the same elevation as the rod 65 and which are parallel to the rod 65, produce the desirable result that the shuttle lifter 52

and the opener 57 can be quickly taken out after removal of the cover plates 61 and can be easily checked, cleaned and reinserted.

While a specific embodiment of the invention has been shown and described, it will be apparent to those skilled in the art that various changes, modifications, substitutions, additions and omissions may be made therein without departing from the spirit and scope of the invention as set forth in the appended claims.

I claim:

1. In a loom for weaving having gripper shuttles for picking weft threads through the shed from a weft thread supply which is located outside of the shuttles: a shuttle picking mechanism, a shuttle receiving mechanism, return means for returning idle shuttles from said receiving mechanism to said picking mechanism, a shuttle carrier adapted to receive a shuttle from said return means and to transport it to the position from which the shuttle is picked, a pin swingably supporting said carrier, the longitudinal axis of said pin being at a right angle to the picking path of the shuttles, a movable support for said pin, and guide means for guiding said support to move in a direction at a right angle to the longitudinal axis of said pin.
2. In a loom for weaving having gripper shuttles for picking weft threads through the shed from a weft thread supply which is located outside of the shuttles: a shuttle picking mechanism, a shuttle receiving mechanism, return means for returning idle shuttles from said receiving mechanism to said picking mechanism, a slide forming part of said picking mechanism, and a shuttle carrier swingably mounted on said slide, said shuttle carrier being adapted to receive a shuttle from said return means and to transport it to the position from which the shuttle is picked, said slide being movable in a direction affording movement of the swing axis of said carrier at a right angle to the picking path of the shuttle.
3. In a loom as defined in claim 2, said slide being in the form of a U-shaped bracket whose legs are slidably supported, a rod connected with said bracket, at the base of the U, and a helical compression spring wound around said rod and having one end connected with the rod, the other end of said spring resting against a stationary part of said picking mechanism.
4. In a loom according to claim 3, a cam, a lever, a cam follower connected with said lever and engaging said cam, and a link positioned substantially parallel to said rod and connecting said lever with said shuttle carrier.
5. In a loom for weaving according to claim 3, in which the gripper shuttles have clamps for gripping a weft thread: an opener for the clamp of a gripper shuttle, said opener being swingably mounted on said slide for swinging on the same axis as said carrier, a cam, a lever, a cam follower connected with said lever and engaging said cam, and a link positioned substantially parallel to said rod and connecting said lever with said opener.
6. In a loom for weaving according to claim 3, in which the gripper shuttles have clamps for gripping a weft thread: an opener for the clamp of a gripper shuttle, said opener being swingably mounted on said slide for swinging on the same axis as said carrier, a first cam, a first lever, a cam follower connected with said first lever and engaging said first cam, a first link connecting said first lever with said opener, a second cam, a second lever, a cam follower connected with said second lever and engaging said second cam, and a second link connecting said second lever with said carrier, said links being positioned substantially parallel to said rod.
7. In a loom for weaving according to claim 6, said cams being formed by grooves in the surface of a drum.
8. In a loom for weaving according to claim 6, in which said first lever is provided with a fork straddling said rod and the latter has a collar adapted to abut against said fork.

9. In a loom for weaving having gripper shuttles for picking weft threads through the shed from a weft thread supply which is located outside of the shuttles, the weft threads being gripped by thread clamps connected with the shuttles: a shuttle picking mechanism, a shuttle receiving mechanism, return means for returning idle shuttles from said receiving mechanism to said picking mechanism, a shuttle carrier adapted to receive a shuttle from said return means and to transport it to a position from which the shuttle is picked, a pin swingably supporting said carrier, the longitudinal axis of said pin being at a right angle to the picking path of the shuttles, a movable support for said pin, guide means for guiding said support to move in a direction at a right angle to the longitudinal axis of said pin, and an opener for the clamp of the shuttles, said opener being swingable on the same axis as said carrier.

10. In a loom for weaving having gripper shuttles for picking weft threads through the shed from a weft thread supply which is located outside of the shuttles: a shuttle picking mechanism, a shuttle receiving mechanism, return means for returning idle shuttles from said receiving mechanism to said picking mechanism, and a shuttle carrier adapted to receive a shuttle from said return means and to transport it to the position from which the shuttle is picked, a pin swingably supporting said carrier, the longitudinal axis of said pin being at a right angle to the picking path of the shuttles, a movable support for said pin, and guide means associated with said support for guiding the latter to move in a direction at a right angle to the longitudinal axis of said pin, said carrier being provided with a cover plate having an arcuate edge extending in a direction which is substantially parallel to the picking path.

11. In a loom for weaving having gripper shuttles for picking weft threads through the shed from a weft thread

supply which is located outside of the shuttles: a shuttle picking mechanism having a casing, a shuttle receiving mechanism, return means for returning idle shuttles from said receiving mechanism to said picking mechanism, a shuttle carrier adapted to receive a shuttle from said return means and to transport it to the position from which the shuttle is picked, a pin swingably supporting said carrier, the longitudinal axis of said pin being at a right angle to the picking path of the shuttles a movable support for said pin, guide means for guiding said support to move in a direction at a right angle to the longitudinal axis of said pin, and abutments connected with said casing, said carrier resting against one of said abutments when said carrier is in one of its extreme positions.

12. In a loom for weaving having gripper shuttles for picking weft threads through the shed from a weft thread supply which is located outside of the shuttles: a shuttle picking mechanism, a shuttle receiving mechanism, return means for returning idle shuttles from said receiving mechanism to said picking mechanism, and a shuttle carrier adapted to receive a shuttle from said return means and to transport it to the position from which the shuttle is picked, said carrier being swingable for movement between a shuttle receiving position and a shuttle picking position, said carrier including a portion horizontally overhanging the longitudinal axis of the shuttle and being carried by the shuttle when the shuttle is in the picking path, means for withdrawing said overhanging portion from the vertical plane of the picking path coincident with the swinging of the carrier from its picking position to its receiving position.
